METHOD OF MAKING A BAG HAVING A
FILLER MOUTHPIECE IN ONE END

Howard A. Wolf, Philadelphia, Pa., assignor to
Elias Wolf, Howard A. Wolf, and Walter L.
Wolf, copartners trading as Wolf Brothers,
Philadelphia, Pa.

Application December 1, 1945, Serial No. 632,176

1 Claim. (Cl. 93—35)

1

This invention relates to the method of making filter bags having a filler mouthpiece secured in the end thereof, adapted to be secured to an outlet from an exhauster of a vacuum cleaner, and for reinforcing a bag mouth.

One of the objects of my invention is the provision of a method for securing a mouthpiece in one end of a bag formed of pervious paper or fabric, adapted to be used in connection with a vacuum cleaner and arranged to receive a nozzle to which the outlet from the exhausting fan extends, the other end of which is closed, so that the air delivered to the bag will filter through the wall of the bag leaving the dust in the bag.

Another object of my invention is the provision of a simple method whereby a relatively strong mouthpiece can readily be secured to the walls of a tube having parallel sides, or a tube having infolded sides, such as commonly made on machines for making paper bags in a continuous manner.

Another object of my invention is the provision of a method whereby a mouthpiece having infolded sides can be secured to the infolds of an infolded tube, whereby portions of the infolds of the mouthpiece are securely cemented to the inner faces of portions of the infolds of the bag forming tube, while the inner faces of the remaining portions of the infolds of the tube are cemented to portions of the panels overlying the infolds, while the remaining portions of the panels are cemented to the outer faces of the panels of the filling tube, whereby the entire outer face of the filling tube is sealed to one end of the bag, and the inner faces of the infolded portions of the tube beyond the mouthpiece are sealed to each other without cementing any portion of the outer face of the tube in the infolds to an adjacent portion of the tube within the infolds.

Referring to the accompanying drawing in which:

Fig. 1 is a face view partially in section of the open end of one form of bag made in accordance with my invention;

Fig. 2 is a sectional view on the line 2—2 of Fig. 1;

Fig. 3 is a view showing a portion of Fig. 2, and in which the parts have been greatly enlarged for clearness;

2

Fig. 4 is a view similar to Fig. 1 in which a mouthpiece is secured in a tube without infolds;

Fig. 5 is a diagram illustrating one method of assembling the several parts for cementing;

Fig. 6 is a vertical section through the open end of a bag, which is reinforced both internally and externally as on the line 6—6 of Fig. 7 after the former has been removed; and

10 Fig. 7 is a sectional view as on the line 7—7 of Fig. 6 showing a former in position in the assembled members.

The finished bag, which is formed of pervious paper stock or fabric, comprises panel portions

15 10 which extend across the entire width of the bag on opposite sides from an outer fold 12 at one side of the bag to an outer fold 12 at the other side of the bag, and infolded members 14 at each side of the bag which extend from folds

20 12 to a fold 16 forming the apex of the infold, and cemented to the inner face of portions of each panel 10 and portions of each infolded member 14 is a filling mouthpiece of impervious material, and when cemented within the pervious

25 tube is substantially the same shape as the pervious tube with the exception of the width of the panels 10' and infolded members 14', which also extend from folds 12' to folds 16' of the mouthpiece.

30 The inner faces of the central portions of the panels 10 of the tube are cemented to the outer faces 10' of the mouthpiece, while the outer faces of the infolded members 14' of the filling mouthpiece are cemented to portions of the inner faces of the infolded members 14 of the tube,

35 and the inner faces of the portions of the panels 10 of the tube and the inner faces of the portions of the infolds 14 of the tube are cemented to each other from the folds 12 to folds 12' of the mouthpiece.

It will thus be observed that the entire outer face of the mouthpiece is cemented to some portion of the inner face of the tube, while the remaining portions of the inner faces of the

40 45 tube extending beyond the mouthpiece are cemented to each other, whereby the one end of the tube is sealed around the mouthpiece while the portions of the tube beyond the mouthpiece are sealed to each other.

50 The other end of the tube may be closed in any manner either before or after securing the

mouthpiece in position, so that a filter bag is provided which is sealed at all points except the opening through the mouthpiece.

The various parts are preferably sealed to each other by a band A preferably of impervious paper, extending around the entire outer face of the tube, and is provided with cementitious material on its inner face *a*, or the face contacting with the tube, and after the mouthpiece is assembled with the tube the parts are pressed into contact with each other, to cause the cementitious material to pass through the pervious material of the tube, to cement the mouthpiece to the tube and to cement the portions of the tube extending beyond the mouthpiece to each other.

The cementitious material may be either any of the thermal setting cements, glue or any adhesive adapted for cementing bags.

In Fig. 4, I have shown a filter bag made from a plain tube without infolds and in which the outer face of an impervious mouthpiece B is cemented to portions of the inner faces of the sides C and C' of a pervious tube, while the inner faces of the sides C and C' of the tube extending beyond the mouthpiece are cemented to each other by cement passing from the inner faces of impervious strips D and D' through the sides C and C', and which may be assembled and formed as described with relation to Fig. 7.

In Figs. 6 and 7, I have illustrated portions of a bag in which the entire open end of a pervious bag is reinforced and is formed by first placing a narrow impervious strip E on a former or support F, then placing the open end of a pervious bag or bag forming tube section as G, over the impervious strip E, and then wrapping a strip H about the tube G over the strip E either or both strips having one side coated with cement, with the cement in contact with the tube G, and then applying pressure to the assembly to cause the cement to flow through the pervious tube from strip to strip, to cause the tube G to be cemented to the adjacent faces of the strips E and H.

The tubes from which the bags are made as before stated are made in a continuous manner, and can readily be cut to the required length automatically by the tube forming machine.

These tubes are also made to exact widths, so that the distance between the inner folds 16 of the infolded portions are substantially the same distance apart during the entire run of the machine as the infolds are made over fixed formers, so that the infolds of each of the blanks of a predetermined size are the same distance apart.

Both forms of mouthpieces as well as the tubes E may be made on similar machines and cut to length and when formed in this manner the inner folds 16 of the tubes will perfectly nest in the inner folds 16 of the infolded mouthpieces, while the tubes E will perfectly nest in the tubes G.

Various devices may be devised for carrying out the steps of nesting the mouthpiece in an infolded tube, then applying a cement coated strip of impervious material in contact with the outer faces of the infolded members 14 and in contact with the outer faces of the panels 10 of the tube and then causing the cement to pass through the portions of the tube under the cement coated strip to the underlying portions of the mouthpiece and both the portions of the tube beyond the outer folds of the mouthpiece which are in contact with each other, so that the entire inner surface of the tube is cemented to either the outer face

of the panels of the mouthpiece or the overlying portions of the tube to each other, while the outer surfaces of the infolds of the tube will be prevented from contacting with these surfaces due to uncoated back of the imperforate strip A.

In Fig. 5, I have shown one form of apparatus which is of material assistance in assembling the parts, and in which 40, 40 designate metallic strips each of a width to extend from one outer fold 12' at the side of one panel 10', to the other outer fold 12' at the other side of the said panel of the mouthpiece, the tube is then placed over the mouthpiece with the infolds thereof nested in the infolds of the mouthpiece with the inner folds 16 of the tube in contact with the inner folds 16' of the mouthpiece.

Strips A with their coated sides outermost are then bent about positioning blades 42, 42 on each side of the tube, or towards the outer faces of the tube infolds 14, and strips A are also placed on the panels 10 in the same vertical plane as the strips on the blades 42. The blades 42 are then moved towards each, preferably in unison to seat the folded strip A in the inner fold 16 of the mouthpiece, and as the outer folds 12' of the mouthpiece are held in fixed positions by the strips 40, the strips A can be tightly forced into the folds.

It is immaterial whether the strips A are placed on the panels 10 before or after the strips A are seated in the infolds, but after all adhesive strips have been positioned the entire assembly can be pressed together between pneumatic pressing members, as the metal strips 40 may be so mounted as to permit their movement towards each other.

The interior of the pressing members may be maintained under a predetermined pressure and temperature to cause thermo-setting cement to pass through the pervious tube and set the same, or dry the strip A if moistened to soften cement previously applied to the strips.

If desired the strips may be coated with glue just prior to the placing of the strips.

After the assembly has been pressed, the cemented assembly is drawn from the strips 40 and 42.

The form shown in Fig. 4 can be formed by inserting the mouthpiece in the open end of the tube at any desired position, after which adhesive strips A are placed over the outer face of the tube, and then pressed between pneumatic pressing members as above described.

It will be evident that variations may be made in the invention without departing from the principles thereof as defined in the appended claim.

What I claim and desire to protect by Letters Patent is:

60 The method of making a filter bag having an impervious tubular filler mouthpiece from a bag and a mouthpiece each having infolds at its opposite sides and panels extending from side to side of the infolds, comprising nesting within the open end of the bag an open ended tubular mouthpiece having infolds of less depth than the infolds of the bag in contact with portions of the inner faces of the panels and portions of the faces of the infolds of the bag, then placing a strip of impervious material having a cement on one face thereof over the entire outer portion of the bag including the infolds at the space desired to be cemented, and then causing the cement to flow through the bag, to cement the mouthpiece to portions of the panels and por-

tions of the infolds of the bag, and also the inner faces of the portions of the panels of the bag extending beyond the junctions of the panels and infolds of the mouthpiece and the bag to the adjacent portions of the infolds of the bag.

HOWARD A. WOLF.
